GRINDSTONE

Willis E. Danback, Tiffin, Ohio, assignor to The
Cleveland Quarries Company, Cleveland, Ohio,
a corporation of Ohio

Application January 24, 1939, Serial No. 252,648

3 Claims. (Cl. 51—167)

The present invention relates to grindstones and more particularly to the frames thereof.

An object of the present invention is the provision of a novel and improved grindstone or grindstone frame which will be simple and rugged in construction and inexpensive to manufacture.

The invention resides in certain details of construction and combinations and arrangements of parts and further objects and advantages of the invention will be apparent to those skilled in the art to which this invention relates from the following description of the embodiment thereof described with reference to the accompanying drawings forming a part of this specification, in which similar reference characters designate corresponding parts and in which:

Fig. 1 is a perspective view of a grindstone embodying the present invention;

Fig. 2 is a side elevational view of the grindstone shown in Fig. 1;

Fig. 3 is a front elevational view of the grindstone shown in Figs. 1 and 2;

Fig. 4 is a section approximately on the line 4—4 of Fig. 2;

Fig. 5 is a section approximately on the line 5—5 of Fig. 1;

Fig. 6 is a section approximately on the line 6—6 of Fig. 3;

Fig. 7 is an enlarged view of a portion of Fig. 1; and

Figs. 8 and 9 are views similar to Figs. 5 and 6 but show a modified construction.

Referring to the drawings, the reference character A designates a grinding stone or wheel of conventional construction, preferably made of sandstone, rotatably supported in a frame designated generally by the reference character B. As shown, the frame B comprises two continuous tubular side members 10 and 11 of general triangular shape as shown in the drawings, the sides of which are of unequal length and the corners of which are rounded to give a more pleasing appearance. One of the longer sides of each of the two side members 10 and 11 forms the base and the grinding wheel is located between the upper parts of the side members which converge, as viewed in a vertical plane through the axis of rotation of the wheel, see Fig. 3. The side members 10 and 11 are connected together at opposite sides of the wheel. In the preferred embodiment of the invention shown, both of these connections are identical and each includes two plates welded to opposite side members and detachably bolted together. As shown, the front connection in-

cludes the two plates 12 and 13 and the rear connection the plates 14 and 15. In the present instance, the plates 12 and 14 are welded to the side member 10 while the plates 13 and 15 are welded to the side member 11. Each of these plates is provided with a plurality of bolt holes, through the medium of which the plates are bolted together by means of bolts 16. The construction is such that the side members 10 and 11 can be dismantled to facilitate shipping, etc., and readily assembled when desired. An alternative construction is shown in Figs. 8 and 9 wherein the connections between the side members 10 and 11 merely consist of single plates 17 and 18 welded to the opposite side members. This construction is preferred where there is no necessity for dismantling the frame.

The grinding stone or wheel A is fixed to a tubular sleeve 20 which in turn is fixed to a horizontal shaft 21 rotatably supported in anti-friction bearings 22 carried within bearing members 23 detachably connected as by bolts 24 to a plate or member 25 welded to the upper part of the side members adjacent what might be referred to as the apex of the frame. Outside of 20 the bearing members and at both sides, the shaft 21 is provided with cranks 26 and the wheel A is adapted to be rotated by double treadles 27, fulcrumed or pivoted in short tubular members 28 welded to the front sides of the 30 side members 10 and 11. The treadles 27 are operatively connected to the cranks 26 by pitmans 30, the upper ends of which are connected to the cranks 26 through the medium of anti-friction bearings 31.

The grindstone shown in the preferred embodiment of the invention also includes a bicycle-type seat 32 fixed to a seat support or rod 33 comprising a V-shaped tubular member welded to the upper plate 15 of the connection between the 40 side frames 10 and 11 at the rear of the grinding stone. The seat support 33 also carries a splash guard 34 adjustably secured thereto by means of a clamp member 35. An arm 36 bolted to a member 37 welded to one of the side 45 members, in the present instance the right-hand member 11, carries a water cup 38 directly above the grinding stone. The base of the side members 10 and 11 is slightly raised intermediate the ends so that the grindstone will better set on 50 an uneven surface. While the side members 10 and 11 and the seat rod or support 33 are shown as being made of round tubular material, it is to be understood that the material used may be solid as well as tubular and that the cross sec- 55

tion thereof may be other than round, for example, square, rectangular, triangular, angular, etc.

From the foregoing description of the preferred embodiment of the invention, it will be apparent that the objects of the invention herefore enumerated and others have been accomplished and that a simple, rugged and inexpensive grindstone or grindstone frame has been provided. While the preferred embodiment of the invention has been described in considerable detail, it is to be understood that the invention is not limited to the particular construction shown but that the construction shown may be varied within the scope of the invention and it is my intention to cover hereby all adaptations, modifications and uses which come within the practice of those skilled in the art to which the present invention relates and I particularly point out and claim as my invention the following:

1. A grindstone comprising a frame including side members formed of welded-up tubular material, a grinding wheel, means for connecting said side members together including cross members at the front and rear of said grinding wheel welded to said side members, bearing members for rotatably supporting said grinding wheel, brackets welded to said side members on opposite sides of said grinding wheel, means for detachably securing said bearing members to said brackets, double treadles for rotating said grinding wheel, means for pivotally connecting said treadle members to said side members, a V-shaped bracket made of tubular material one prong of which is welded to said cross member at the front of said grinding wheel, and a seat secured to the other prong of said V-shaped bracket.

2. A grindstone comprising a frame including

side members formed of welded-up tubular material, a grinding stone or wheel, means for connecting said side members together including cross members at the front and rear of said grinding wheel welded to said side members, 5 bearing members for rotatably supporting said grinding wheel, brackets welded to said side members on opposite sides of said grinding wheel, means for detachably securing said bearing members to said brackets, double treadles for rotating 10 said wheel, means including tubular members welded to said side members for pivotally connecting said treadle members to said side members, a V-shaped bracket made of tubular material one prong of which is welded to said cross 15 member at the front of said grinding wheel, and a seat secured to the other prong of said V-shaped bracket.

3. A grindstone comprising a frame including side members formed of welded-up tubular material, a grinding stone or wheel, means for connecting said side members together including cross members at the front and rear of said grinding wheel welded to said side members, 20 said cross members comprising two parts detachably secured together, bearing members for rotatably supporting said grinding wheel, brackets welded to said side members on opposite sides of said grinding wheel, means for detachably securing said bearing members to said brackets, double 25 treadles for rotating said grinding wheel, means for pivotally connecting said treadle members to said side members, a V-shaped bracket made of tubular material one prong of which is welded to said cross member at the front of said grinding wheel, and a seat secured to the other prong of said V-shaped bracket. 30

WILLIS E. DANBACK.
